UNITED STATES PATENT OFFICE.

WILLIAM DAVIS HOOKER, OF ST. LOUIS, MISSOURI.

VALVE-MOVEMENT FOR DIRECT-ACTING ENGINES.

SPECIFICATION forming part of Letters Patent No. 313,863, dated March 17, 1885.

Application filed January 18, 1884. (No. 101.)

To all whom it may concern:

Be it known that I, WILLIAM DAVIS HOOKER, a citizen of the United States, residing at St. Louis, in the State of Missouri, have invented 5 certain new and useful Improvements in Valve-Movements for Direct-Acting Engines; and I do hereby declare the following to be a full, clear, and exact description of the invention, such as will enable others skilled in the art to 10 which it appertains to make and use the same.

My invention relates to improvements in valve-movements for direct-acting engines. An essential feature of the mechanism which I employ in the present invention is found in 15 a patent granted to me for improvements in "Hand-Lever Attachments for Steam-Pumps," dated January 3, 1882, No. 251,715, in which a right-angle oscillating shaft or bearing and a reciprocating arm or lever are 20 shown.

The invention herein set forth and claimed 25 contemplates improvements whose object may be briefly stated as follows: first, to provide, in connection with the right-angle oscillating shaft and its reciprocating arm, above mentioned, a simple, durable, and efficient valve-movement for working the valve or valves of a direct-acting engine in such a manner as to cause the reversal of said valve or valves, and 30 thereby render the reciprocating movement of the engine continuous as long as steam is supplied to drive it; second, to produce a short movement of the valve as compared with the movement of the main piston of the engine, and 35 to make this movement adjustable so as to vary the movement of the steam-valve as desired; third, to provide a means whereby the main piston shall be caused to slow down gradually at the termination of its stroke, thereby preventing it from striking the cylinder-heads, and also causing the pump-valve to beat quietly, producing a more steady pressure in the pump; fourth, by the reaction of the means 40 for slowing down the main piston at the end of its stroke to give a quicker start to it on its return-stroke; and, fifth, to compel the main valve to stop at the right point and not overrun its proper stroke. To attain these objects I construct a valve-movement mechanism in 45 connection with the right-angle oscillating shaft and reciprocating arm, which I have adopted from my previous patent, hereinbe-

fore mentioned, substantially in the manner about to be described.

Referring to the accompanying drawings, 55 which illustrate what I consider the best means for carrying the invention into practice, Figure 1 is a side elevation of the device; Fig. 2, a transverse vertical section. Fig. 3 is a modified form of the arm L; Fig. 4, a detail of the dog.

Similar letters of reference indicate corresponding parts in the figures.

A is a portion of the steam-cylinder; A', the valve-chamber mounted thereon. B is a portion of the pump. The cylinder and pump are connected by the yoke C. Through the stuffing-boxes of the yoke slides the piston-rod D. To one end of this rod is fastened the steam-piston, and to the other end is fastened the 70 pump plunger or piston in the manner usually followed in steam-pumps of this construction.

On the piston-rod D, midway between the two pistons, is secured the hub E, to which is pivoted the driving-arm F. The arm or rod F passes loosely through a hub, G', which is formed at a right angle, and integral with or rigidly secured to the oscillating pin or shaft G. This latter is supported in a bearing, H, mounted on and fastened to the yoke C, or 80 any part of the machine most convenient.

On the right-angle oscillating pin G is loosely fitted the valve-arm J, the opposite end of which is pivoted to the valve-stem K of the engine. At the side of the valve-arm J, and 85 rigidly attached to the pin G, is the arm L, which has dogs m m fitted to it. The dogs lie on opposite sides of the arm J, and may be adjusted so as to lie nearer to or farther away from each other. For this purpose slots l are 90 cut in the arm L, and the dogs are provided with nuts, as shown, to set them in any relative position. The arm J above the pin G is provided with an extension or projection, s, and the support H has stops p p on either side 95 of the part s to limit its movement.

The driving-arm F extends some little distance above the hub G', and is provided with a coiled spring, n, and an adjustable collar, O, with a set-screw, o'. The spring n bears 100 against the hub G' and collar O, and is adjusted by the latter.

The slots l in the arm L may be inclined, as shown in Fig. 1, or horizontal, as shown in

Fig. 3, in which latter case set-screws will be necessary to hold the dogs *m* in place. The dog *m* is provided with a rubber cushion, *m'*, to strike on the arm *J*.

5 The parts thus constructed and combined operate as follows: When the piston-rod *D* is moved in either direction, the arm *F* is carried to an inclined position, and causes the right-angle pin *G* to be partially turned. The arm *L*, 10 rigidly secured to the pin *G*, is moved with it, and the dogs *m m*, coming alternately in contact with the valve-arm *J*, (which is loose upon the pin *G*,) push said arm in one direction or the other, thereby causing the reversal of the engine. During the movement of the piston toward the end of a stroke the arm *F* will be drawn 15 out and the spring *n* compressed, by means of which the engine will be slowed down at the end of the stroke and the piston prevented from striking the ends of the cylinder, and 20 the pump-valves will be seated quietly. On the engine being reversed and commencing the return-stroke the recoil of the compressed spring *n* will give back the power stored in 25 it, and the engine will respond by starting back quickly. All slamming and jars are prevented, and the parts of the engine and pump are saved from much wear and breakage, while a decided increase in point of speed in starting 30 on the return-stroke is insured.

The construction by which the valve is moved by the operation of the dogs *m* on the rigid arm *L* upon the swinging valve-arm *J* produces a short movement of the valve, compared with the movement which the main piston has, and this movement may be made greater or less by setting the dogs closer together or farther apart.

A positive stop is given to the valve-arm *J* 35 by the contact of the projection *s* with the stops *p p* on either side, and the valve is prevented from overrunning its stroke and compelled to stop at the right point.

Modifications within wide limits may be made in the form and manner of connecting 45 the parts without departing from the spirit or sacrificing the advantages of my invention.

Having thus described my invention, what I desire to claim and secure by Letters Patent is—

50 1. The right-angle oscillating shaft *G* and driving-arm *F*, pivoted to the piston-rod and passing through said shaft, in combination with the valve-arm *J*, fitted loosely to the oscillating shaft *G* and pivoted to the valve-stem, 55 and the arm *L*, having the dogs *m m*, fastened to and moving with the oscillating shaft, as described, and for the purpose set forth.

2. The combination, with the right-angle oscillating shaft or pin *G* and driving arm *F*, 60 of the valve-arm *J*, swinging on the oscillating shaft and provided with the extension or projection *s*, the arm *L*, rigidly secured to the shaft *G*, and provided with the dogs *m m*, and the stops *p p*, for contact with the projection 65 *s*, to limit the stroke of the valve, as set forth.

3. The combination, with the driving-arm *F* and oscillating shaft *G*, through which the driving-arm loosely passes, of the spring *n*, exerting its force to retard and accelerate the 70 movement of the steam-pump at the end and beginning of the strokes, respectively, substantially as set forth.

4. The combination of the oscillating pin or shaft *G* and means for operating it, with the 75 swinging valve-arm *J* and rigid arm *L*, having the adjustable dogs *m*, for contact with the valve-arm, as set forth.

In testimony whereof I affix my signature in presence of two witnesses.

WILLIAM DAVIS HOOKER.
